UNITED STATES PATENT OFFICE.

WALTER C. WHITE, OF LOS ANGELES, CALIFORNIA, ASSIGNOR TO INTERNATIONAL COUPLERS COMPANY, OF LOS ANGELES, CALIFORNIA, A CORPORATION OF CALIFORNIA.

TRAIN-PIPE COUPLING.

1,204,219.

Specification of Letters Patent.

Patented Nov. 7, 1916.

Application filed March 20, 1913, Serial No. 755,697. Renewed February 7, 1916. Serial No. 76,775.

To all whom it may concern:

Be it known that I, WALTER C. WHITE, a citizen of the United States, residing at Los Angeles, in the county of Los Angeles and 5 State of California, have invented certain new and useful Improvements in Train-Pipe Couplings, of which the following is a specification.

This invention relates to train-pipe couplings, and has for its object the provision 10 of coupler heads of such construction as to effect fluid-tight joints around the registering ports of opposed heads, and a still further object of the invention is to provide 15 an improved construction of coupler head whereby the ports will be held in fluid-tight relation when the heads are coupled and injury to the gaskets or packing around the ports during the coupling or uncoupling operations will be prevented.

These stated objects, and such other objects as will incidentally appear as the description of the invention proceeds, are attained in a mechanism of the character 25 illustrated in the accompanying drawings, and the invention resides in certain novel features which will be particularly pointed out in the claims following the description.

In the drawings: Figure 1 is a vertical 30 longitudinal section through two coupled heads, showing my present improvements; Fig. 2 is a horizontal section taken on the line 2—2 of Fig. 1, the line 1—1 in this figure indicating the plane of the section 35 shown in Fig. 1 in order that said Fig. 1 may be more readily understood; Fig. 3 is a plan view of two heads in coupled relation; Fig. 4 is an end elevation of one of the coupler heads; Fig. 5 is a detail perspective view of one of the electrical terminals; Fig. 6 is a detail view of a gasket; Fig. 7 is a detail view showing the construction 40 of the port in which the gasket is fitted; Figs. 8 and 9 are side views of the coupler head.

In carrying out my present invention, I employ a coupler head 1 which is provided with a plurality of longitudinally extending chambers 2, 3 and 4 into which, through the 45 rear end of the coupler head, the train-pipes extend. In the present illustration, I have shown a steam pipe 5 entering the lowermost chamber, while the pipe 6 carrying the

air for the brakes is shown as entering the intermediate chamber, and in the upper 55 chamber is received the ends of an electrical conductor or cable 7. It will be understood, however, that the usual air signal line or pipe may be carried into the chamber immediately above the chamber receiving the air 60 brake line, and the electrical conductor may be housed in a fourth chamber. The electrical cable may be utilized for forming circuits for the train telephone and telegraph systems and may, if desired, be utilized as 65 the engineer's signal. When a part of this electrical conductor is utilized as the engineer's signal line, the air signal line will, of course, be omitted.

Each coupler head is supported upon a 70 hanger depending from the frame of the car or from the car coupling heads or draw bars and comprising, generally, a shelf 8 to support the head, vertical guides 9 rising from the said shelf, and suitable braces 75 10 extending from the shelf and the said guides to the suspending members of the hanger. A pipes carrier 11 is fitted in the guides 9 and the train-pipes extend through this carrier, as will be readily understood. 80 The particular type of hanger forms no part of my present invention, however, and for that reason is not shown herein in detail, the form illustrated being that disclosed in my application filed June 25, 1912, 85 Serial No. 705,818.

The coupler head is provided with rearwardly extending arms 12 at its upper and lower ends which are longitudinally slotted to receive securing bolts 13 by which they 90 are attached to the pipes carrier and permitted to move relatively to the said carrier when the heads are being coupled and afterward as the car couplings become taut. Each head comprises a body portion 14 having a front face 15 which is disposed obliquely to the longitudinal axis of the head or body, and, in the said obliquely disposed front wall, I form a plurality of ports 16 corresponding in number with the train-pipes to be coupled. The ports are substantially elliptical in outline, as shown most clearly in Fig. 5, and in the walls of the ports are formed recesses or seats to receive the gaskets 19. It will be readily noted 100 from Figs. 2 and 5 that the gaskets extend 105

substantially longitudinally of the coupling and are provided with wide end faces forming elongated bearing surfaces to meet similar surfaces on an opposed coupler and provide a large fluid-tight joint between the passages of opposed heads. As the coupling heads wear, the gaskets slide upon each other and overlap so as to compensate for wear and, at the same time, leave an open port ample to permit flow of fluid through the coupling. The gaskets are elongated so that in their extreme overlapping relation an open passage will be provided of a diameter not less than the width of the port. The wide end faces of the gasket will preserve a tight joint under this extreme condition. At the ends of the ports are segmental flanges 17 which coact with the walls of the seats to form pockets into which the flanges 18 on the gaskets may be sprung and retaining lugs or lips 20 are formed at the inner sides of said recesses to extend over the inner sides of the gaskets and thereby aid in keeping the gaskets in place. The outer wall of the coupler head extends from the extremity of the face 15 at an angle to the longitudinal axis of the coupler head, as indicated at 21, so that the front end of the coupler head body has a wedge formation. In rear of this inclined face 21, the outer side of the body extends at a lesser angle to the longitudinal axis of the body, as shown at 22, and upon this outer side of the body is an offset 23 so formed as to present upper and lower rearwardly converging ribs 24 and a convex surface 25 between the said ribs, said surface springing from the outer wall of the head so that the end of the guide arm on an opposed coupler head coming into engagement with the said surface will be deflected transversely and the opposed coupler head, consequently, brought into close contact with the head to which it is to be coupled. Springing from the side of the coupler head opposite that provided with the offset 23, is a guide arm 26 which has upper and lower edges flat or straight at their rear extremities and then curved toward each other so that the arm terminates in a point 27 adapted to enter between the ribs 24 and ride upon the convex surface 25. As shown most clearly in Figs. 2 and 3, the inner surface of this guiding arm is shaped to provide an inclined face 28 at its rear extremity disposed at an angle slightly more abrupt than the angle of the face 21 of the coupler head, and, in advance of this said inclined face 28, the guiding arm is provided with a short longitudinally extending portion 29 adapted to bear against the outer surface 22 of the opposed coupler head. When the opposed heads come together the extremity of the surface 21 on one head will engage and ride upon the surface 28 of the opposed head so

that while the heads will be deflected laterally only a minute portion of these surfaces will be in contact and, consequently, friction between these portions of the heads will be minimized. Moreover, a space will be left between the heads through which dirt may escape and a vertical groove 50 is formed at the rear extremity of the front face 15 of the head so that dirt cannot accumulate between the heads and interfere with the successful operation of the device. The provision of this groove 50 permits the extreme end of an opposed head to crowd up into the angle at the base of the guiding arm without hindrance from any dirt that may be pushed in advance thereof, so that, under all conditions, a fluid-tight engagement of the gaskets will be effected.

In advance of the longitudinally extending surface 29, the guiding arm is provided with an outwardly and forwardly inclined surface 30 extending to the point 27 of the arm, and having an angle of inclination greater than that of the surface 22 of the body. Should the heads to be coupled be out of alignment as they come together, the surfaces 30 of the respective guiding arms 26 will impinge against the surfaces 21 of the opposing heads and the two heads will thereby be shifted transversely so as to be brought into alignment. It will also be noted that a slight vertical movement will be imparted to the heads relative to each other by the ribs 24 engaging the upper and lower edges of the guiding arm, and to further provide for such vertical movement and thereby insure the ports of the coupler heads being brought into exact registry, I secure to the top and bottom of each head, plates 31 which project laterally beyond the side of the coupling head body opposite that side from which the guiding arm 26 projects and constitute wings between which the end of the guiding arm on an opposed head enters. The projecting portions of these plates or wings striking the upper or lower edge of the guiding arm will be thereby caused to ride upwardly or downwardly so that the desired vertical registry of the ports will be quickly accomplished. The plates or wings 31 are flat and are engaged by the rear flat portions of the upper and lower edges of the guiding arms, so that, when the heads are coupled and the guiding arm is extending between the wings, angular movement of the heads relative to each other will be prevented. The inner edges of these wings or plates 31 are provided with shoulders or offsets 32 in order to increase the width of the wings toward the inner face of the coupling head to engage the guiding arm more quickly than would otherwise be the case.

The several train-pipes will be permitted to telescope within the respective chambers of the coupler heads in order to avoid in-

jury from the impact of opposing heads in the act of coupling and also to accommodate vibration or other movement during the travel of the cars. In the present instance, 5 the steam pipe 5 is shown projecting into the chamber 4 of the coupler head, and a packing 33 is provided around the said pipe so as to prevent leakage from the chamber of the coupler head. The air brake line 6 10 enters a sleeve 34 extending from a piston 35 arranged within the chamber 3 of the coupler head which constitutes a cylinder. After the heads have been coupled, the air is cut into the train line 6 and will flow 15 through the same until it meets a closed cock on an adjacent car or at the end of the train. The pressure of the pipe will then react upon the piston 35, so that the said piston will be forced backward and, acting upon the end 20 of the train-pipe, will move the said pipe outwardly and cause a shoulder thereon to bear against the pipes carrier or an abutment plate of the hanger, so that further rearward movement of the coupler head will 25 be prevented and the coupled heads held together, this operation being specifically set forth in my application, Serial No. 705,818, above mentioned.

The cables 7 carrying the electrical conductors of the train are secured to plugs 36 30 within the upper chamber 2 of the coupler head and these plugs are embedded in an insulating block 37 provided on its opposite sides with longitudinal ribs 38 adapted to engage longitudinal grooves formed in the ends of the chamber 2, and retaining springs 40 are secured at the ends of the said grooves to engage the ends of said ribs and thereby hold the plugs within the coupler heads. It will be noted upon reference 45 to Fig. 6 that the outer ends of the insulating blocks or sleeves and the plugs are beveled upon an angle coinciding with the angle of inclination of the front face of the coupler head body and the ends of the plugs project slightly beyond the end of the insulating sleeve, so that, when the coupler heads come together, the plugs will be brought into close contact and the electric 50 circuits established. The ribs 38 serve to prevent rotation of the plugs within the body of the coupler head, so that they will always be in position to engage the plugs of an opposing coupler head and thereby establish the electric circuit with certainty. 55 Should it be necessary for any reason to remove the plugs, as for instance, to substitute a new plug for a worn out plug, the springs 40 may be readily depressed so as to disengage the ribs 38, after which the plugs 60 may be at once withdrawn. It will be understood, of course, that the springs may be secured upon the plug and engage sockets in the walls of the chamber which would be 65 a mere reversal of the illustrated arrange-

ment. A rubber ring or other resilient cushion 70 41 is fitted upon the end of the plug so that the plugs may readily adjust themselves and will not be apt to be injured by the impact in coupling.

It will be readily understood from the foregoing description, taken in connection with the accompanying drawings, that I have provided a train-pipe coupling which may be produced at a low cost and applied to 75 a car in an inexpensive manner. In my present coupling, the chambers within the coupling heads will be in a direct line with the train-pipes, so that all turns in the air and steam passages are eliminated and, consequently, the frictional resistance is overcome. 80 It will also be noted that the present invention minimizes the number of parts necessary to effect a close tight coupling and also reduces the weight of the coupling. As 85 the gaskets are disposed at an angle to the axis of the coupler heads, unnecessary pressure upon the same is avoided, while, at the same time, they will be held in sufficiently close engagement to form a fluid-tight joint 90 between the opposed couplers. By fitting the train line telescopically within a sleeve projecting from the piston through the agency of which pressure is exerted to hold the coupler heads together, I provide for an 95 extreme longitudinal movement of the coupler heads in the operation of the device or during the travel of the cars. The several beveled or inclined faces of the coupling heads and the guide arms are so disposed 100 that the gaskets are fully protected against injury as the heads come together and twisting of the gaskets, as they move upon each other after being coupled, is prevented by 105 the engagement of the guide arm and the 110 upper and lower wings.

What I claim is:—

1. A coupler body having a rigid guide arm extending forwardly from one side and having a front vertical edge extending the 110 entire height of the body and spaced from said arm, a vertical face extending from said edge to the base of said guide arm, a second vertical face extending from said edge in divergent relation to the first-mentioned face, said second vertical face terminating in a 115 vertical side disposed at a slight angle to the longitudinal axis of the body, a lateral offset on the body at the rear of said vertical side, and rearwardly converging lateral ribs at 120 the upper and lower edges of said offset, said offset and ribs being adapted to be engaged by the guide arm of an opposed head.

2. A coupler head for train-pipe couplings 125 having a body and a guide arm rigid with and extending forwardly from one side thereof, the outer side of the body and the inner side of the guide arm being each provided with a plurality of vertical deflecting surfaces and a vertical groove being formed 130

at the junction of the body and the arm, the engaging deflecting surfaces on the arm and the body being arranged at slightly different angles of inclination whereby both ends 5 of the guide arm may bind against the outer side of an opposed head with the intervening portions of the opposed surfaces out of contact.

3. A coupler head for train-pipe couplings having vertical faces of unequal length diverging rearwardly from a front vertical edge disposed at one side of the longitudinal axis of the head, the longer face extending in a single plane across the 10 longitudinal axis of the head, flat wings extending laterally in parallel planes from the top and bottom of the head at the side having the shorter face, and a guide arm extending forwardly from the opposite side of 15 the head at the rear end of the longer vertical face and having flat upper and lower 20

surfaces at its rear extremity to fit between and engage the wings on an opposed head.

4. A coupler head for train pipe couplings having a forwardly extending tapered rigid 25 guide arm on one side, the opposite side having its forward portion arranged at an angle to the longitudinal axis of the head to present an inclined deflecting surface to be engaged by the guide arm of an opposed 30 head, a lateral offset provided on said side at the rear of said deflecting surface and having a horizontally convex outer surface, and rearwardly diverging ribs at the upper and lower edges of said offset. 35

In testimony whereof I affix my signature in presence of two witnesses.
